UNITED STATES PATENT OFFICE

NICHOLAS A. NICHOLSON, OF JOHNSTOWN, PENNSYLVANIA

MOTION-PICTURE APPARATUS

Application filed February 1, 1930. Serial No. 425,298.

This invention relates to motion picture apparatus, and aims to provide novel means controlled by an abnormal condition of the film strip passing through the machine, for releasing a fire shutter to cut off the light rays projected from the lamps of the machine and protect the film strip from the intensive heat of the lamps.

An important object of the invention is to provide a device of this character which will be pneumatically controlled to the end that air drawn through a tube, will act to hold valves to their seats, retaining the various elements of the mechanism in their active 15 positions, but releasing the various elements to permit them to move to their abnormal conditions, when the vacuum within the tube is dissipated.

A still further object of the invention is to provide means for automatically breaking the circuit to the motor employed in operating the machine, when the fire screen or shutter moves to its active position.

With the foregoing and other objects in view, which will appear as the description proceeds, the invention resides in the combination and arrangement of parts and in the details of construction hereinafter described and claimed, it being understood that changes 25 in the precise embodiment of the invention herein disclosed, may be made within the scope of what is claimed, without departing from the spirit of the invention.

Referring to the drawings:

Figure 1 is a diagram illustrating a pneumatic control device constructed in accordance with the invention.

Figure 2 is an enlarged sectional view illustrating the shutter and its support as secured 40 to the machine.

Figure 3 is a sectional view taken on line 3—3 of Figure 2.

Figure 4 is a sectional view taken on line 4—4 of Figure 2.

Figure 5 is a detail view of one of the valves.

Figure 6 is a sectional view through a valve and pipe to which it is connected.

Referring to the drawings in detail, the reference character 5 designates the main tube

of the apparatus, and as shown this tube connects with the tube 6, which in turn connects with the tube 7 that communicates with the blower casing 8.

The reference character 9 designates a valve 55 which controls the passage of air through the tube 5. The blower not shown, and which operates in the casing 8, is of the usual and well known construction, the same being operated by means of the belt 10 that moves over the 60 pulley 11, mounted on the motor shaft 12, the motor also providing power to operate the motion picture machine with which the device is used.

The upper end of the tube 5 extends laterally, as at 13, and is open to the atmosphere so that under abnormal conditions, air may be drawn into the tube 5, through the laterally extended end 13 thereof. Mounted at the open end of the tube 5, is a sliding valve 14 which 70 normally closes the end of the tube 5. Springs 15 are connected with the valve 14 and act to return the valve to its normal closed position when the machine continues operation.

A guard plate indicated by the reference 75 character 16 is supported adjacent to the film strip feed spool 17, the plate 16 being substantially long and curved so that the film strip may pass freely thereunder. Extending downwardly from the plate 16, is an arm 80 18 that has a lateral horizontal arm 19 disposed directly under the film strip, which is indicated by the letter A. Thus it will be seen that should the film strip become taut the film strip will engage the arm 19 to swing 85 the plate 16 in one direction, and should the film strip buckle, the film strip will pile up under the plate 16 causing it to tilt.

Connected with the plate 16, is an arm 20 that moves with the plate, the arm 20 being 90 connected to the arm 21 of the valve 14, through the rod 22. As the plate 16 is rocked under the action of the film strip, the rod 22 is moved to slide the valve 14 to its open position to allow air to be drawn through the 95 tube 5. The tube 23 also connects with the tube 5 and has an open end normally closed by means of the pivoted valve 24 that has an upstanding finger 25 resting in the groove of the member 26 that is connected to the gover- 100

nor 27, to move therewith. The governor 27 is mounted on the shaft 28, which in turn is operated by the gearing and mechanism employed in operating the moving picture machine, with the result that should the machine speed up, or be retarded in its action, the valve 24 will be moved to allow air to be drawn into the tube 23 and tube 5, dissipating the vacuum within the tube, for purposes to be hereinafter more fully described.

10 Tube 29 also connects with the tube 5 and is provided with a pivoted valve 30 that breaks communication between the tube 29 and atmosphere, under normal operating conditions. Extending upwardly from one end of the valve 30, is an arm 31 that is adapted to be engaged by the arm 32 extending downwardly from the arm 33 connected with the arm 34 that in turn is provided with a roller 35 engaged by the film strip A.

15 A weight 36 is mounted on the arm 33 and acts as a counterbalance for the arm. Should the film strip break at a point between the spools 36' and 37, the weight 36 will overbalance the arm 33, causing the arm 32 to engage the arm 31 to move the valve 30 to its open position and allow air to be drawn into the tube 5, through the tube 29. The weight 36 is adjustable along the arm 33.

20 The reference character 38 designates a tube that is also in communication with the tube 5, the outer end of the tube 38 being extended upwardly terminating in the housing 39. The housing 39 is supplied with a bearing 40 into which the shaft 41 extends, there being provided a set screw 42 for holding the shaft 41 in position. This shaft 41 provides a support for the tubular bearing 43 that extends through an opening in the front wall of the housing 39, the tubular bearing 43 being formed integral with the arm 45 to which the shutter 46 is secured. A handle 47 is secured to the arm 45 and affords means whereby the shutter may be manually moved to its active or inactive position.

25 Secured to the shutter 46, is a rod 48 on which the adjustable weight 49 is mounted, the weight being held in its positions of adjustment, by means of the set screw 50. Extending laterally from the tubular bearing 43, is a lug 51 that contacts with the under surface of the arm 52 which is pivotally mounted within the housing 39 by means of the bracket 53. Under normal conditions, 30 the arm 52 bearing against the lug 51, holds the tubular bearing and shutter connected therewith, in their inactive positions.

35 At the outer end of the arm 52 is a valve 54 that is adapted to move over the open end 60 of the pipe 38 to normally close the pipe 38, the arm 52 being held in such position by the suction of air through the tubes of the device, created by the blower operating in the blower housing 8.

40 65 Mounted on the tubular bearing member

43, is a mercury switch 55 that is in circuit with the motor that operates the moving picture apparatus, through the wires 56, 57, switch 58 and wires 59 and 60.

45 This mercury switch is so constructed that when the arm 45 is in a horizontal position, the circuit to the motor will be completed, but when the arm 45 moves to a position to move the shutter 46 to its active position, the mercury switch will operate to break the circuit to the motor, causing the motor to cease its operation.

50 The reference character 61 designates a heating device that includes a resistance coil 62 which is in circuit with the wires 56 and 57, which in turn are in circuit with a source of electricity supply, through the wires 63 and 64 respectively, the latter wire being supplied with a switch 65 to control the electric energy passing through the wires to the resistance coil 62.

55 The heating device 61 is hollow so that heat may pass upwardly therethrough, the heating device being in circuit with the tubes 5 and 6, through the tube 66.

60 Should it be desired to create a vacuum in the tubes of the apparatus, by the action of heat, the valve 9 is operated to establish communication between the tubes 6 and 66. The switch 65 is operated to complete the circuit to the resistance coil, to the end that the heat in the heating device will create a vacuum in the various tubes.

65 The reference character 67 designates a valve which may be operated to cut off communication between the blower housing and various tubes of the apparatus.

70 It might be further stated that the shutter 46 is provided with an offset portion 10' defining a shoulder to engage the finger 11' when the shutter swings to its active position.

75 In the operation of the device the valves 9 and 67 are moved to positions as shown by Figure 1 of the drawings, whereupon the blower is set in operation to the end that air is drawn through the tube 5 creating a vacuum in the tube 5 to draw the arm 52 into engagement with the open end of the tube 38. While the arm 52 is in this position, the shutter is held in its inactive position by the contact of the arm 52 with the lug 51 of the tubular bearing.

80 120 Should the film strip break at a point between the spools 36' and 37, the weight 36 will overbalance the arm 33 causing the arm to fall downwardly to move the valve 30 to its open position, allowing air to be drawn through the tube 29, dissipating the vacuum in the tube 5. The arm 52 is now released, and the weight of the shutter causes the shutter to fall to its active position.

85 125 When the valves 24 and 14 are operated to allow air to enter the tube 5, the vacuum in

tube 5 is dissipated and the arm 52 is operated to release the shutter.

I claim:

1. In a motion picture apparatus, a fire shutter, an arm for normally holding the shutter in its inactive position, a tube disposed adjacent to the arm, means for creating a vacuum in the tube to draw the arm into engagement with one end of the tube, a tube 10 extending laterally from the first mentioned tube and having its free end open to the atmosphere, a valve for normally closing the free end of the last mentioned tube, and means actuated by the film strip passing 15 through the apparatus for actuating the valve to permit air to enter the tubes and release the arm and shutter.

2. In a motion picture apparatus, a pivoted shutter, a shutter controlling means including a tube, means for creating a vacuum in the tube to hold the shutter in its inactive position, a tube extending from the first mentioned tube and having its free end open to the atmosphere, a valve at the free end of 25 the last mentioned tube for normally closing the tube to the atmosphere, a weight on the valve for regulating the movements of the valve, means controlled by the action of a film strip for actuating the valve, and means 30 for drawing air through the tubes.

3. In a motion picture apparatus, a pivoted shutter, an arm on which the shutter is mounted, a main tube, means for creating a vacuum in the main tube to operate the arm 35 and hold the shutter in its inactive position, a branch tube having communication with the main tube and having an open outer end, a valve for closing the outer end of the tube, a motor for operating the apparatus, a governor 40 controlled by the motor, said governor being connected with the valve and adapted to operate the valve to admit air to the tubes to dissipate the vacuum in the tubes to release the arm.

4. In a motor operated motion picture apparatus, a pivoted shutter, an arm for holding the shutter in its inactive position, a main tube, means for creating a vacuum in the main tube to hold the shutter in its inactive 50 position, a branch tube in communication with the main tube, a valve on the outer end of the branch tube and having an upstanding finger, a governor controlled by the action of the motor operating the moving picture 55 apparatus, a grooved member operated by the governor, said finger operating in the groove of the grooved member to open the valve to admit air to the tubes for releasing the arm and shutter.

5. In a motion picture apparatus, a pivoted shutter, an arm on which the shutter is mounted, a main tube, means for creating a vacuum in the main tube to operate the arm and hold the shutter to its inactive position, 60 a branch tube having communication with the

main tube and having an open outer end, a valve for closing the outer end of the tube, a motor for operating the apparatus, a governor controlled by the speed of the apparatus, and said governor being connected with the valve and adapted to operate the valve to admit air to the tube to dissipate the vacuum in the tubes to release the arm and shutter.

In testimony that I claim the foregoing as 70 my own, I have hereto affixed my signature.

NICHOLAS A. NICHOLSON.
